REMOVABLE BRUSH ATTACHMENT

Filed Nov. 24, 1926

Inventor,
Eugene F. Martinet

Attorney.

UNITED STATES PATENT OFFICE

EUGENE F. MARTINET, OF CLEVELAND, OHIO, ASSIGNOR TO THE P. A. GEIER COMPANY, OF CLEVELAND, OHIO, A CORPORATION OF OHIO

REMOVABLE-BRUSH ATTACHMENT

Application filed November 24, 1926. Serial No. 180,512.

My invention relates to improvements in removable brush attachment, and has for its object the provision of means for removably but securely mounting a brush device upon a suction nozzle. More particularly, this invention contemplates the provision of means for sliding the brush longitudinally into and out of its operative position upon the nozzle, for accurately holding it in alignment with the open mouth of the nozzle without choking the opening, and for compensating any wear or looseness of fit.

The embodiment of my invention comprises an elongated, open-mouth suction nozzle having a longitudinal rim and an associated, centrally slotted brush attachment provided with coating slides fitting removably upon the rim, together with resilient means, preferably within the slide, for temporarily holding and positioning the brush upon the nozzle.

The several details of construction, the utility and advantages of my instant invention, however, may best be explained in connection with the accompanying drawings illustrating preferred embodiments thereof, wherein:

Figure 1, is a view in front elevation of a nozzle and brush attachment;

Fig. 2, is a view thereof in side elevation;

Fig. 3, is a plan view, partially broken away and in section, showing the brush member, and

Fig. 4, is a similar view of a slightly modified form.

Throughout the several figures of the drawings I have employed the same character of reference to indicate similar parts.

As best shown in Fig. 2, the elongated hollow suction cleaner nozzle *a*, terminating the tubular portion *a'* adapted for a hose attachment, is provided with longitudinal rim members *a''* peripherally enclosing the mouth of the nozzle. A common use of such nozzle members requires the aid of a brush

and it is obvious that secure and ready means for attaching and detaching the brush member are practically essential.

The coacting brush member *b* is provided with longitudinal slides *b'* open at one end and closed at the other to permit the mouth of the nozzle accurately to register with the slot *b''* when the brush is positioned upon the nozzle. A spring wire *c*, or opposing spring wires *c, c'* are positioned within the slides *b'* so as to engage the rims *a''* of the nozzle when the brush is in place.

Since the mouth and rims of the nozzle are symmetrical, the brush member may be slid thereon from either end and brought into accurate register with the nozzle opening without care or attention on the part of the user. The spring or springs within the slides afford resilient means for holding the brush member removably in place and for compensating as to looseness of fit or wear. Thus the slide members may be constructed to afford ample clearance with respect to the receiving rim of the nozzle, so that the brush may be most readily mounted in position or removed therefrom, as varying working conditions may require.

Having now described and shown preferred embodiments of my invention, I claim as new and desire to secure by Letters Patent, the following:

1. The combination with a suction cleaner nozzle having an elongated mouth provided with peripheral rim members at front and back, of a removable brush therefor formed with a central opening and provided with grooved slides adapted to engage said rim members and with a terminal stop, and resilient means mounted in the sliding grooves and reacting laterally against a rim member to hold the brush so that its central opening is approximately in register with the mouth of the nozzle, substantially as set forth.

2. The combination with a suction cleaner nozzle having an elongated mouth provided

with peripheral rim members at front and back, of a removable brush therefor formed with a central opening and provided with grooved slides adapted to engage said rim members, and resilient means mounted in a sliding groove of the brush and reacting laterally against the nozzle to hold the brush in position so that its central opening is approximately in register with the mouth of the nozzle, substantially as set forth.

10 In testimony whereof I do now affix my signature.

EUGENE F. MARTINET.
